UNITED STATES PATENT OFFICE.

FRANK C. MILLER, OF EASTON, PENNSYLVANIA.

ADJUSTABLE WINDOW-SCREEN.

SPECIFICATION forming part of Letters Patent No. 543,261, dated July 23, 1895.

Application filed January 4, 1895. Serial No. 533,856. (No model.)

To all whom it may concern:

Be it known that I, FRANK C. MILLER, a citizen of the United States, residing at Easton, in the county of Northampton and State of Pennsylvania, have invented certain new and useful Improvements in Adjustable Window-Screens; and I do hereby declare the following to be a full, clear, and exact description of the invention, such as will enable others skilled in the art to which it appertains to make and use the same.

My invention relates to improvements in adjustable window-screens of that class designed to be tightly fitted in and removed from windows of certain limited sizes, and which employ, in connection with a rigid screen-frame, two sliding panels, which are slidably fitted to the ends of the screen-frame, and which panels are normally pressed away from the screen-frame by tension-springs, and the outward movement of which sliding panels is limited by stop devices.

The object that I have in view in the present invention is to produce a strong and simple screen of few parts, which can be manufactured at a low price, and to provide improved devices whereby the user can conveniently and readily adjust and handle the screen, either to place it in or remove it from the window-frame.

With these ends in view my invention consists in the combination, with a rigid frame having the usual screen-wire attached thereto and provided in its end rails with transverse centrally-disposed openings or passageways, of sliding panels fitted to the ends of the screen-frame to slide thereon, two central pull-bars, which pass loosely through the central openings in the end rails of the screen-frame, having their outer ends rigidly fastened to the sliding panels and provided at their inner ends with finger-pieces, which extend at right angles to the shanks of the pull-bars and thus lie at right angles to the wire fabric from which said finger-pieces extend, whereby the operator is enabled to easily grasp the pull-bars, the central arrangement of which bars to the frame enables the screen to be easily balanced in the hands of the operator for the purpose of conveniently adjusting the screen to or removing it from the window-frame, springs which normally force the sliding

panels away from the end rails of the frame, and stops to limit the outward movement of said sliding panels.

My invention further consists in the combination, with a rigid screened frame and sliding panels constructed with closed sides and outer ends to leave the inner ends of said panels open for the reception of the ends of the screened frame, of stop-rods attached to the sliding panels at points within the top and bottom rails of the screened frame and fitted between the closed sides of the end panels and the end rails of said screened frame, so as to be housed and protected by the closed sides of the sliding panels, with which said stop-rods are movable, the inner ends of said stop-rods terminating flush with the inner edges of the closed sides of the sliding panels, and said inner ends of the stop-rods bent to form lugs, in the path of which lie the end rails of the screen-frame, so that the lugs on the stop-rods will abut against the end rails of the frame to limit the outward movement of said sliding panels, the central pull-bars attached to the sliding panels, and coiled springs fitted on the pull-bars and bearing against the sliding panels and end rails of the rigid screen-frame.

The special arrangement of the stop-bars between the sliding panels and the end rails of the screen-frame, and each rod having one end attached to the panel and its free end formed with a hook or lug to take against an end rail of the frame, produces a simpler and cheaper screen than heretofore—consisting of fewer parts, hence cheaper to manufacture—and avoids recessing or slotting the horizontal rails of the screen-frame, which has heretofore been customary in order to accommodate the stop-rods and the pins or studs with which the stop-rods are designed to engage.

To enable others skilled in the art to understand my invention, I have shown the preferred embodiment thereof in the accompanying drawings, forming a part of this specification, and in which—

Figure 1 is an elevation looking at one side of a screen constructed in accordance with my invention. Fig. 2 is a horizontal sectional view on the plane indicated by the dotted line $x x$ of Fig. 1. Figs. 3 and 4 are enlarged

detail sectional views on the plane indicated by the dotted line y y of Fig. 1, showing the position of one slideable panel and one stop-rod when the panel is drawn in toward the 5 end rail of the screen-frame and when it is forced out to its full limit away from the screen-frame. Fig. 5 is a full-sized horizontal 10 sectional view similar to Fig. 2, in order to clearly illustrate the pull-bar and the spring, together with a part of the screen-frame and the slideable panel.

Like letters of reference denote corresponding parts in all the figures of the drawings.

The screen-frame A consists of the end rails 15 a a and the top and bottom rails b b , which are suitably joined together in a strong and rigid manner. Over this frame is stretched the usual woven-wire fabric B, which has its edges confined between the rails a b of the 20 frame A and the cleats or strips b' , which are laid upon and fastened to the frame A.

C D denote the slideable panels, which are fitted to the ends of the frame to inclose the rails a a thereof and to slide freely over the 25 same. Each panel is made in the form of a boxing or housing, and consists of two side pieces c c' and an end piece c'' , which is fitted between and fastened to the side pieces c c' , whereby the panel has two closed sides and 30 one closed end, while the other end of the panel is left open to receive the end of the screen-frame. The length of the panel is equal to the width of the frame A, and the combined width of the two panels is such that 35 the screen may be materially widened to fit in window-frames which vary in width, but which window-frames exceed the width of the screen-frame A.

The space between the sides c c' of the 40 panel slightly exceeds the thickness of the end and side rails of the screen-frame, in order that the panel may move freely over the end of the frame when it is desired to retract or pull the panel in toward the frame and 45 also to permit the stop-bars E F to lie between the slideable panels and the end rails of the frame A, whereby the stop-bars are combined with the frame and the panels in a way to avoid cutting slots or recesses in the frame 50 A, as has been customary heretofore, but which practice is objectionable, as it not only involves additional machine-work in the preparation of the rails for the screen-frame, consequently adding to the cost of manufacture, but also involves a special construction 55 of stop bar or plate and the use of pins or studs to co-operate with said stop bar or plate.

In my screen the end and side rails are made 60 from ordinary stock and without any additional work to prepare them for use in a screen, and the stop-bars E F are made from single lengths of wire or steel rod, which are suitably bent into shape and attached in a simple way to the panel and arranged so as 65 to act with the end rails a a to limit the outward displacement of the panel. As stated,

each stop-bar is cut in suitable length from a piece of wire or rod, and one end is bent to form the panel-attaching prong e , while the other end of the wire is bent at right angles 70 to produce the stop lug or hook f . There are two of these stop-bars provided for each panel, and they are attached to the panel near the ends thereof, but at points within the side rails b b of the screen, in order that the stop 75 hooks or lugs f of the bars may extend toward the screen fabric B and the end rails a a of the frame B may lie in the path of the hooks or lugs f to adapt the latter to come in contact with the inner edge of the end rail when 80 the bars and panel are forced outward under the pressure of the coiled spring I. These stop-bars are thus arranged near the sides of the frame, within the side rails thereof, and between the pair of stop-bars for each panel 85 is arranged the pull-bar H, the latter being disposed centrally with relation to the frame. The stop-bars are fastened to one side c of the panel, and they extend alongside of and close to the side c of the panel, said bars passing over the end rail a of the frame and having their free ends flush with or terminating within the sides of the panel, the hooks or lugs f extending from the panel toward the screen fabric, in order that said lugs may 95 take or bear against the end rails of the frame, as has been explained.

Each pull-bar H, of which two are provided for the two slideable panels, is made in a single piece, with a plain smooth shank, a threaded 100 attaching end h , and a right-angled finger-piece h' . The shank of the pull-bar passes loosely through an aperture i cut in the center of the end rail a of frame A, and its threaded end h is screwed into the end piece c'' of the 105 slideable panel. The finger-piece h' extends at right angles to the length of the pull-bar, and when the bar is in position on the screen this finger-piece preferably extends from the screen fabric toward the operator, whereby 110 the pull-bar can be firmly grasped between the finger and thumb of the hand without the hand coming in contact with the screen fabric B. This finger-piece is preferably in the 115 form of a broad curved hook, as shown in the drawings, although it may be in the shape of a loop or eye which stands at right angles to the length of the pull-bar and extends out from the screen fabric. These finger-pieces of the pull-bars can thus be easily grasped by 120 the operator to retract the panels C D toward the screen frame A, and by having the pull-bars disposed centrally with relation to the frame A the screen is made to balance itself in the hands of the operator, thereby enabling both panels to be retracted at once and the screen to be conveniently operated and adjusted to place it within, or take it from, the window-frame.

The springs I are of the coiled-wire variety, 130 and they are fitted loosely around the plain smooth shanks of the pull-bars, one end of

each spring bearing against a slidable panel and the other end of said spring bearing against an end rail *a* of the screen-frame.

It will be noted that the stop-bars and the coiled springs are practically housed entirely within the slidable panels *C D*, so that the parts are protected from injury by the panels themselves.

My improved screen, constructed as herein shown and described, possesses many practical advantages over other screens in that a fewer number of parts are necessary to produce a screen having all the advantages of prior devices and the parts are arranged and disposed to better advantage with a view to securing the necessary functions. It follows that as a less number of parts are employed the screen is simpler in construction and is cheaper to manufacture. At the same time the parts are not liable to get out of order and the screen is more durable and satisfactory. Importance is attached to the construction and organization of the pull-bars as herein described, because the screen is made to balance itself nicely in the hands of the operator and a very secure hold can be obtained on the finger-pieces of the pull-bars, which enables the screen to be lifted, held, and adjusted by simply grasping the finger-pieces with the hands.

In order that the advantage of my screen may be apparent in so far as its simplicity and cheapness are concerned, I may state that in some of the prior screens which have been devised and placed on the market there are no less than sixteen (16) different and distinct parts, while in my improved screen there are only ten parts necessary to be made and assembled together. The screen can thus be made and sold by the manufacturer at a lower price than ordinary screens, and in addition to the advantage to the manufacturer it is more convenient to the user in that it is more easily adjusted than other screens, is less liable to get out of order, and more durable.

Having thus fully described my invention, what I claim as new, and desire to secure by Letters Patent, is—

1. A window screen comprising a frame having the wire fabric, the slidable end panels which inclose the ends of the frame and have the sides *c, c'* adapted to slide over the end rails thereof, the stop bars *E, F*, arranged between one side, *c*, of each panel and the end rail, *a*, of the frame, the outer ends of said bars fastened to the panels and the inner free ends having hooks or lugs *f* that extend inwardly in the path of the end rails and abut against the inner edge thereof, the pull bars and pressure springs, substantially as and for the purposes described. 5c 55 60

2. A window screen comprising a rigid frame having the wire fabric, the box-like panels *C, D*, fitted to the ends of said frame to inclose the end rails thereof, the central 65 pull bars *H* passing loosely through the end rails of the frame, having their outer ends fastened to the panels, and provided at their inner ends with the right angled finger pieces that extend outward from the wire fabric, the 70 coiled springs fitted on said pull bars, and the pair of stop bars *E, F*, for each panel, which stop bars are disposed on opposite sides of the pull bar but within the side rails of the frame, and each stop bar having a prong which 75 is fastened to the panel and said bar passing between the end rail of the frame and one side of the box-like housing, and having at its free end a hook or lug *f* which extends toward the screen fabric and is adapted to bear 80 against the inner edge of the end rail of said frame, all arranged and combined substantially as and for the purposes described. 85

In testimony whereof I affix my signature in presence of two witnesses.

FRANK C. MILLER.
